METALLIC GRAVE VAULT

Allen F. Beck, Columbus, Ohio

Application July 10, 1937, Serial No. 152,978

6 Claims. (Cl. 27—35)

This invention relates to improvements in metallic burial vaults of the type utilizing separable base and cover members wherein the base is formed with an elevated horizontally disposed 5 casket receiving platform and depending marginal flanges on which the weight of the vault and its contents are received.

When a relatively heavy metallic burial vault and the contents thereof are placed on the bottom of a grave with only the limited area of the marginal edges of the vault base in contact with the soil, it may happen that the combined weight of the vault, its contents and the superposed soil, cause the base to sink into the soil or to become out of level, so that moisture and sub-surface water may find entrance to the interior of the vault with resulting undesirable conditions.

It is an object of the present invention to provide a metallic burial vault wherein the base 20 thereof, below the elevated casket receiving platform, is provided with metallic weight receiving horizontally placed panels which materially augment the soil engaging area of the vault base so that undesirable sinking or settling of the vault 25 as a whole in a grave following interment will be prevented.

Another object of the invention resides in providing the longitudinal sides of the vault base with depending marginal ribs which are so arranged 30 that their lower surfaces will be disposed in a plane slightly below the plane of the base panels, so that said ribs may function as runners, without interference on the part of the panels and in facilitating sliding movement of the vault 35 when positioned on a hard supporting surface.

A further object of the invention resides in providing said base with a manually controlled means for governing the operation of latching devices used in retaining the cover of such a 40 vault in assembled relationship with the vault base, the latching devices and the operating mechanism therefor forming the subject matter of my co-pending application Serial No. 179,165, filed December 10, 1937.

45 For a further understanding of the invention, reference is to be had to the following description taken in connection with the accompanying drawings, wherein:

Fig. 1 is a perspective view looking upwardly 50 toward the bottom of one end of a metallic grave vault made in accordance with the present invention;

Fig. 2 is a vertical longitudinal sectional view 55 taken through one end of the metallic grave vault and disclosing more particularly the cross sec-

tional formation of the area augmenting panels in the bottom of the vault base and the latch operating mechanism carried thereby;

Fig. 3 is a vertical transverse sectional view taken through the lower portion of the grave vault at one side thereof and disclosing the latch mechanism for uniting the cover of the vault with the base, the runner ribs of the vault base and the reenforcing weight receiving panels in the bottom of the base;

Fig. 4 is a detail horizontal sectional view taken through the vault base and disclosing in plan one of the base panels and the latch operating mechanism carried thereby;

Fig. 5 is a detail perspective view of the operating lever for actuating the latch mechanism;

Fig. 6 is a detail sectional view disclosing the lever latching lug employed in holding the operating lever in a position retaining the spring actuated latching devices associated with the 20 lever in retracted order, the plane of the figure being indicated by the line VI—VI of Fig. 4;

Fig. 7 is a detail perspective view of one of the latch springs;

Fig. 8 is a detail perspective view of one of the 25 latch devices;

Fig. 9 is a detail sectional view taken through the lower portion of a vault which has been provided with a slightly modified type of base panel.

Referring more particularly to the drawings, 30 the numeral 1 designates the base section of a metallic grave vault and the numeral 2 the usual, open-bottomed cover section thereof. These parts are formed from pressed steel plate and are adapted to receive a casket and, when assembled, to protect the latter following interment.

The base section 1, in the present instance, involves an elevated horizontal platform 3, upon which the casket rests. The platform terminates in depending, marginally located side and end 40 walls 4 and 5 respectively, which terminate at their lower edges in outwardly and horizontally disposed flanges 6. The flanges 6 of the side walls 4 terminate in relatively deep reenforcing runner ribs 7, while the corresponding flanges of the end walls 5 terminate in similar reenforcing ribs 8, which are not quite as deep as the ribs 7. By this construction, when the vault rests on a hard surface, only the ribs 7 engage with said surface so that the weight of the vault will be confined 50 to a limited area permitting of convenient sliding movement of the vault along or over such a hard surface.

The cover section 2 includes vertical side and end walls 9 and 10 respectively which terminate 55

at their lower edges in inwardly directed horizontal flanges 11 which, as shown in Figs. 2 and 3, rest upon the flanges 6 of the base section, the flanges 11 terminating in upwardly directed extensions 12 which are inclined to engage with the slightly inclined side and end walls 4 and 5 of the base section.

In order to provide for an increased area of support for the vault, when the same is positioned 10 in the bottom of a grave and to relieve the ribs 7 and 8 of the weight imposed thereon, as in former constructions, the present invention provides the base section 1, at each end thereof, with a flat metallic plate or panel 13. Each plate or panel 15 is provided with spaced parallel longitudinally extending reenforcing ribs 14 and with upwardly offset marginal flanges 15, which are welded or otherwise secured as at 16 to the under surfaces of the horizontal flanges 6, so that said plates or 20 panels will serve to mechanically strengthen the base construction and at the same time will provide a broad resting area upon which the weight of the vault is received when positioned on a soil bed.

25 Each plate or panel 13 occupies a horizontal plane spaced slightly above the bottom edges of the runner ribs 7, as disclosed in Fig. 3, so that the plates will not interfere with the operation of the runner ribs when the latter engage a hard 30 unyielding base surface. However, the lower surfaces of the ribs 8 at the ends of the base section are disposed substantially in the same plane as the plates or panels. This arrangement provides a strong and substantial base construction 35 which will resist settling of the vault when positioned on a soil bed and enables the weight of the vault to be better distributed on such a yielding bed than when the weight is confined to the ribs 4 and 5, as heretofore.

40 In securing the cover and base sections together, in locked or assembled relationship, the side walls 5 of the base section, contiguous to each end of the vault, are provided with swinging latches 17 of the type illustrated in Fig. 8. These 45 latches are each formed to include a lip 18 which pivotally enters a slot 19 provided in an adjoining wall 4, and positioned beneath the lip 18 is a U-shaped wire spring 20 of the type disclosed in Fig. 7. The U-shaped loop 21 of each 50 spring engages with the inner surface of the latch and terminates in coil convolutions 22, which in turn terminate in short leg projections 23, the latter engaging with the outer surface of the adjoining wall 4 adjacent to the slot 19. 55 Each latch 17 includes a pair of side wings 24 which are received within guiding slots 25 provided in the walls 4. By this construction, the latches are normally forced outwardly to assume the position disclosed in Fig. 3 so that the lower 60 arcuate edges 26 of the wings 24 will be arranged over the upper edges of the extensions 12 provided on the base flanges of the cover section 2, preventing the elevation of the cover section when in assembled relationship with the base 65 section. Each latch is also provided with a pocket 27 which is shaped to receive the U-shaped loop 21 of the spring 20 employed in connection therewith, confining said spring to its operating position.

70 To provide convenient means for retracting the latches and permitting of the separation of the cover section from the base section, each of the plates or panels 13 is provided centrally with an upwardly pressed bearing boss 28, the latter being centrally apertured to receive a headed

5 screw 29, the threaded shank of each screw projecting below the upper wall of the boss 28 to receive a fastening nut 30. The shank of each of the bolts is squared as at 31 where it fits into the correspondingly formed opening provided 10 therefor in the boss 28, so that the bolt does not rotate. Above the squared portion of the shank of the bolt, the said shank is provided below the head thereof, with a circular portion 32, about which is fulcrumed for rocking movement the 15 operating lever 33. A lever 33 is located at each end of the base of the vault and pivotally mounted as described. In its preferred form, each lever, as shown in Fig. 5, is formed from a sheet metal blank which is stamped or pressed to include a pair of upstanding hooks 34 spaced equidistantly on opposite sides of the fulcrum axis of the lever. Also, the lever includes a handle 35 which projects through a slot 36 formed in the end ribs 8, so that the end of the handle 20 will be manually accessible to provide for the oscillation of the lever.

Connected with the hooks 34 of each lever are the end loops 37 of a pair of twisted wire links 38, which links have their end portions outturned 25 as at 39 and are received within openings provided in the inner edges of the wings 24 of the latches 17.

Normally, the springs 20 of said latches serve to maintain the links 38 and the lever 33 in the 30 position disclosed in Fig. 4, with the latches in their active or extended positions. However, to retract the latches to inactive or withdrawn positions, and thereby to permit of the removal of the cover section, it is necessary merely to rock 35 the levers 33 by manual manipulation applied to the outer ends of the handles 35 thereof so that each lever may be oscillated to an extent sufficient to move the latches to their retracted 40 positions. The latches may be maintained so retracted by the engagement of a resilient lip 40, formed with each of the panels or plates 13. The lip is struck upwardly, as shown in Fig. 6, so that the free end thereof is disposed above the plane 45 of the plate or panel from which it is formed.

Thus, when the lever is moved to an extent sufficient to retract the latches, one edge of the handle of the lever will be positioned in engagement with the free end of the cooperative lip so that the lever will be held in such engagement against the pull exercised by the springs 20. To release the lever, it is simply necessary to resiliently elevate the handle portion thereof so that the engagement between the lever and the lip 40 will be broken and the springs 20 allowed 50 to act in further rocking the lever and moving the latches to their extended positions.

In the modified form shown in Fig. 9, the marginal flanges are omitted from the plate 13a and the flanges 6a of the vault base 1a are formed 60 to include downwardly directed bosses 41. This type of panel is secured to the base by spot welding the former to the lower surfaces of the bosses. While panels of this form do not possess as much 65 rigidity as the form previously described after being attached to the base, they will function equally as well.

The present invention thus provides a strong and substantial base construction for metallic grave vaults wherein the weight of the vault is 70 distributed over supporting surfaces to prevent undesired settling of the vault in somewhat yieldable soils. Also, by the provision of the runner ribs, the augmented bearing surfaces supplied by the plates or panels 13 will not interfere with 75

sliding movement of the vault on hard or unyielding surfaces. The plates or panels 13 tie the side and end walls 4 and 5 of the base section together, producing greater mechanical strength.

5. Moreover, the plates or panels 13 provide a convenient base for the support of the mechanism for effecting the simultaneous actuation of the spring pressed latches.

What is claimed is:

10. 1. A base section for metallic grave vaults comprising a sheet metal body formed to include a relatively elevated casket receiving platform, depending side and end walls, outwardly directed flanges at the lower edges of said side and end walls and longitudinally extending runner ribs formed with said flanges, and a metallic bearing plate extending transversely of the base section and secured to said flanges, said plate having the bearing surfaces thereof arranged in

15. 20 a horizontal plane spaced slightly above the base engaging surfaces of said runner ribs.

25. 2. A base section for grave vaults comprising a sheet metal body formed to include an elevated platform, depending side and end walls and outwardly directed and longitudinally ribbed base flanges, and a plurality of flat weight supporting plates secured to said base flanges, said plates serving to sustain the weight of the base section and devices imposed thereon when the base sec-

30. 30 tion is positioned on a soil bed, the longitudinal ribs of the flanges formed in connection with the side walls of said base section being formed to extend slightly below the horizontal plane of said plates to maintain the plates spaced above an

35. 35 unyielding base surface.

3. A base section for metallic grave vaults comprising a sheet metal body having a horizontally extending platform, depending side and end walls provided on said platform, a laterally directed flange formed at the lower edges of said side and end walls, longitudinally extending depending ribs formed with said flanges, said ribs being spaced from the side and end walls to provide seats, and metallic bearing plates extending transversely of said base section, the end and a side edge portion of said plates being positioned in engagement with and secured to said seats.

4. A base section for metallic grave vaults

comprising a sheet metal body having a horizontally extending platform, depending side and end walls provided on said platform, a laterally directed flange formed at the lower edges of said side and end walls, longitudinally extending depending ribs formed with said flanges, said ribs being spaced from the side and end walls to provide seats, metallic bearing plates extending transversely of said base section near the ends thereof, and upwardly offset flanges provided at one side and the end edges of each plate, said flanges being secured to the seats on said base section.

5. A base section for metallic grave vaults comprising a sheet metal body having a horizontally extending platform, depending side and end walls provided on said platform, a laterally directed flange formed at the lower edges of said side and end walls, longitudinally extending depending ribs formed with said flanges, said ribs being spaced from the side and end walls to provide seats, metallic bearing plates extending transversely of said base section near the ends thereof, and upwardly directed reenforcing flanges provided on the side and end edges of said plates, the flanges on one side and the ends of said plates terminating in lateral extensions for engagement with said seats, said flanges being secured to said seats.

6. A base section for metallic grave vaults comprising a sheet metal body having a horizontally disposed platform, downwardly directed walls provided at the sides and the ends of said platform, horizontal flanges projecting from the lower edge of said side and end walls, longitudinally extending depending ribs provided on said flanges, said ribs being spaced from said walls to provide seats at the lower ends of said walls, the ribs on the flanges at the sides of said base projecting a greater distance from the flanges than the ribs at the ends of said base, and transversely extending load-receiving plates positioned beneath said base, said plates having raised flanges at the ends and sides for engagement with said seats, said flanges being elevated a distance slightly less than the height of the ribs at the sides of said base.

ALLEN F. BECK.
